UNITED STATES PATENT OFFICE.

HARRY KRAM, OF NEW YORK, N. Y.

DESIGN FOR SILK, FABRIC, OR LEATHER.

46,029.

Specification for Design.

Patented June 30, 1914.

Application filed April 16, 1914. Serial No. 832,390. Term of patent 3½ years.

To all whom it may concern:

Be it known that I, HARRY KRAM, a citizen of the United States, residing at New York city, in the county and State of New York, have invented a new, original, and ornamental Design for Silks, Fabrics, or Leather, of which the following is a specification, reference being had to the accompanying drawing, forming a part thereof.

The figure is an elevational view of a portion of a fabric containing my new design.

I claim:

The ornamental design for silk, fabric, or leather, as shown.

HARRY KRAM.

Witnesses:

CHAS. DOYNE,

CLARICE FRANCK.
